UNITED STATES PATENT OFFICE.

CHARLES F. PFLANZE, OF ST. LOUIS, MISSOURI.

MACHINE FOR ATTACHING STRINGS TO ENVELOPS.

1,340,909.

Specification of Letters Patent.

Patented May 25, 1920.

Application filed June 18, 1917. Serial No. 175,349.

To all whom it may concern:

Be it known that I, CHARLES F. PFLANZE, a citizen of the United States of America, a resident of the city of St. Louis, State of Missouri, have invented certain new and useful Improvements in Machines for Attaching Strings to Envelops, of which the following is a full, clear, and exact description, reference being had to the accompanying drawings, forming a part of this specification.

My invention relates to improvements in machines for attaching string to envelopes, and the like. The main object of the invention is to produce a machine of this kind having a simple and highly efficient means for pulling and severing a continuous string, thereby dividing the string into a number of short sections, each of which is attached to an envelop or the like. Briefly stated, the invention comprises a combination of devices coöperating with each other to pull string from a source of supply, to attach the string to an envelop, and to sever the string near the point at which it is attached. These operations are carried on continually with the result of dividing a long string into short sections and securing each section to an envelop. The envelopes are preferably handled by the operator, but all of the other operations may be performed by the combination of devices in the machine.

In the preferred form of the invention, the continuous string passes through a row or pile of perforated washers, and a feeding device is utilized to deliver the washers, one at a time, from an end of the row to a riveting device. A hollow rivet or eyelet is acted upon by the riveting device to secure said eyelet and the washer to an envelop. This operation is performed while a portion of the continuous string is in the washer, and as a consequence the string is securely attached to the envelop. The string is then severed near the point of attachment, and another portion of the string is positively pulled from the source of supply. These operations are performed repeatedly.

With the foregoing and other objects in view the invention comprises the novel construction, combination and arrangement of parts hereinafter more specifically described and illustrated in the accompanying drawings wherein is shown the preferred embodiment of the invention; however, it is to be understood that the invention com-

prehends changes, variations and modifications which come within the scope of the claims hereunto appended.

Figure I is a front elevation of a portion 60 of the machine constructed in accordance with my invention.

Fig. II is a detail view, partly in section, showing the oscillatory gripping and cutting device.

Fig. III is an inverted plan view of the parts shown in Fig. II.

Fig. IV is a plan view of the parts at the lefthand end of Fig. II.

Fig. V is a side elevation of the means for 70 transmitting power to the gripping and cutting devices, the frame of the machine being shown by dotted lines.

Fig. VI is a plan view of the gripping and cutting elements.

Fig. VII is a view similar to Fig. VI showing the gripping and cutting elements in different positions.

Fig. VIII is a fragmentary view showing the riveting device and the means for supplying eyelets, string and washers thereto.

Fig. IX is a view similar to Fig. VIII, showing the parts in different positions and also showing the gripping and cutting devices.

Fig. X is a detail view of an envelop having a string attached to its closure flap.

A designates a main supporting frame mounted upon a vertical column B. The means for securing the string to the envelopes preferably comprises a riveting device including a vertically movable plunger 1 adapted to reciprocate in the frame A, a yieldable pin 2 extending downwardly from said plunger 1, a compression spring 3 arranged within the plunger and tending to force the pin 2 downwardly from the lower end of the plunger, as shown in Figs. I and VIII, and a stationary pin 4 alined with the pin 2, said stationary pin being 100 fixed to a small stationary table 5. 6 designates a chute for conducting hollow rivets or eyelets E to the pin 2. I do not deem it necessary to show or describe the elements within the chute 6, for they do not 105 form part of this invention, and they may be constructed in any suitable manner. The chute 6 can also be moved out of the path of the plunger 1, as shown in Fig. IX.

The means for supplying perforated disks 110 or washers W to the pin 2 comprises a magazine 7 containing a row or pile of the perfo-

rated washers, a long tube 8 extending through the perforations in the washers, and an ejector plate 9 forming a seat for the lowest washer in the magazine. This ejector plate forms a closure for the bottom of the magazine, and it may be reciprocated to deliver the washers, one by one, from the magazine to the pin 2. When the ejector plate 9 occupies the position shown in Fig. 5 IX, the lowest washer in the magazine rests upon the reduced end portion of said plate, and a shoulder 10 on said plate lies adjacent to the edge of the washer. If the ejector plate 9 is moved from the position 10 shown in Fig. IX to the position in Fig. VIII, a washer W will be taken from the magazine and delivered to the riveting device. The ejector plate 9 has a slot 11 so that it can be withdrawn from the position 15 shown in Fig. VIII while the pin 2 is located in said slot.

No invention is herein claimed for the details of construction so far described; however, they constitute a riveting device 20 well adapted for use in combination with the string-cutting and string-pulling devices hereinafter described.

Any suitable operating means may be utilized to shift the ejector plate 9 to the 25 position shown in Fig. VIII, while the pin 2 is in a position higher than the ejector plate. An eyelet E is then delivered to the position shown in Fig. VIII, and the plunger 1 moves downwardly to insert the pin 30 2 through the perforations in the eyelet and washer. The ejector plate 9 is then withdrawn to the position shown in Fig. IX, and the plunger 1 continues its downward movement to upset, or flange, the eyelet as seen 35 in Fig. IX. The eyelet and washer are thus firmly secured to the flap F of an envelop. During the upsetting or riveting operation, the spring pressed pin 2 lies entirely within the plunger 1, and the bottom face of said 40 45 plunger engages the eyelet E to firmly force the lower edge of the eyelet onto the table 5, thereby forming a flange at said lower edge.

S designates a long, continuous string or 50 cord, extending through the tube 8 at the center of the magazine 7 containing the washers W. This string extends entirely through all of the washers, as shown in Figs. I, VIII and IX. When the parts occupy the positions shown in Fig. VIII, the lower portion of the string S extends downwardly from the perforation in the washer W on the outer end of the ejector plate 9. After the eyelet E and washer W have been 55 secured to the envelop, as shown in Fig. IX, the string S is firmly attached between the eyelet and washer, also between the washer and the flap F of the envelop. Thereafter 60 the attached portion of the string is severed 65 at a point near the eyelet, and a pulling de-

vice is actuated to positively pull an additional supply of string through the washers in the magazine 7.

The means for severing and pulling the string preferably comprises an oscillatory arm 12 fixed to a vertical rock shaft 13, the latter being mounted in a stationary supporting arm 14; a blade 15 rigidly secured to the free end of the oscillatory arm 12, and a string gripping device carried by said arm 12. While the washer, eyelet and string are secured to the riveting device (Fig. IX), the arm 12 is actuated to grip the string between the envelop and the source of supply, as will be presently described, and the blade 15 carried by said arm 12 severs the string at a point near the flap of the envelop.

The string gripping device comprises a gripping element 16 fixed to the arm 12, a gripping element 17 in the form of a bell crank lever pivoted at 18 to said arm 12, and a bar 19 pivoted to the short arm of the gripping element 17. The bar 19 is loosely secured to the arm 12 by a pin 20 passing through a slot 21 in said bar 19 and secured to the arm 12.

A spring 22, for closing the gripping device, is secured at one end to the oscillatory arm 12 and secured at the opposite end to a pin 23 extending downwardly from the bar 19. This pin 23 is fixed to the bar 19 and it passes through a slot in the arm 12. The spring 22 tends to retain the gripping device in its closed condition, shown in Figs. II, III, IV and VII. The means for opening the gripping device comprises a stationary cam 24 arranged to coöperate with the roller 25 at one end of the bar 19. The cam 24 is adjustably secured to the bearing 14' by means of a set screw 26. During the operation of severing the string, the latter is gripped by the gripping device, as shown in Fig. VII, and the blade 15 contacts with the string at a point between the gripping 11 elements and the washer W. The oscillatory arm 12 then moves to the position shown by dotted lines in Fig. VII, for the purpose of pulling an additional supply of string from the washer magazine.

The means for oscillating the arm 12 comprises an arm 27 (Figs. I and V) fixed to the shaft 13, a long link 28 connecting said arm 27 to a lever 29, and a rotary cam 30 for actuating said lever.

Immediately before the arm 12 reaches the position shown by dotted lines in Fig. VII, the roller 25 on bar 19 engages the stationary cam 24 so as to impart a longitudinal movement to the bar 19, thereby opening the gripping device and releasing the string. The gripping device is then held in its open position by means of a spring actuated latch dog 31 which coöperates with a lug 32 on the bar 19. The latch dog 31 is 130

pivoted on the pin 20 carried by arm 12. During the return stroke of the oscillatory arm 12, the latch dog 31 retains the gripping device in its open condition and the 5 open gripping elements are eventually located at opposite sides of the string S. To accomplish this, the blade 15 and gripping element 16, moving in the direction indicated by the arrow in Fig. VI, are forced 10 past the string S while the latter is held by the riveting device. The string is thus located between the open gripping elements. The latch dog 31 (Fig. VI) engages a stationary lug 33 depending from a stationary 15 arm 34, and this releases the latch dog from the lug 32 on bar 19. The lug 32 then temporarily engages the stationary lug 33 to retain the gripping device in its open position. However, when the oscillatory arm 20 12 reaches the extreme position shown by full lines in Fig. VII, the lug 32 on bar 19 passes from the stationary lug 33, thereby permitting the spring 22 to close the gripping device on the string. The oscillatory 25 arm 12 then moves from the position shown by full lines in Fig. VII to the position shown by dotted lines, with the result of severing the string, and then pulling the gripped portion of the string away from the 30 riveting device and away from the delivery end of the washer magazine, so as to pull an additional length of string from the lower portion of the washer magazine. The string pulling operation ceases when the 35 gripping device is opened through the medium of the stationary cam 24. The length of the string sections to be severed from the long, continuous string may be varied by adjusting the stationary cam 24, the latter 40 being secured by the set screw 26.

It will be observed that the string is positively severed and pulled from the washer magazine, leaving a free portion of the string hanging from the bottom washer in 45 the magazine. This free portion is afterward attached, with the washer, to the envelop, and the cycle of operations can be repeated an indefinite number of times.

I claim:

50 1. In a machine for attaching string to envelops, the combination of washer applying means whereby the string is secured to the envelops, a string pulling device whereby a portion of the string is pulled through 55 the washer before the latter is applied to an envelop, and automatic severing means for severing the string after it is secured to the envelop, said automatic severing means being arranged to operate between said string 60 pulling device and the washer applying means, so as to sever the end portion of the string beyond said pulling device.

2. In a machine for attaching string to envelops, the combination of washer applying 65 means whereby the string is secured to

the envelops, a string pulling device whereby a portion of the string is pulled from a source of supply to points beyond the washer before the latter is secured to an envelop, said string pulling device being located beyond the washer so as to positively pull said portion of the string away from the washer, and automatic severing means for severing said portion of the string from the source of supply, said automatic severing means being arranged to operate between said string pulling device and the washer applying means, so as to sever the end portion of the string beyond said pulling device. 70 75

3. In a machine for attaching string to envelops, the combination of a washer holding device adapted to hold a row of perforated washers, washer applying means for securing the string and washers to envelops, means for feeding the washers from the delivery end of said row to the washer applying means, an intermittent string pulling device for pulling the string through the row of perforated washers, means for actuating said intermittent string pulling device to positively pull the string away from the delivery end of said row, and severing means whereby the string is severed after each pulling operation, said severing means and string pulling device being arranged to 90 operate in the path of the string at points between said washer holding device and the washer applying means.

4. In a machine for attaching string to envelops, the combination of means for attaching an eyelet and a washer to an envelop, said means comprising a riveting device whereby the string is secured with the eyelet and washer, an intermittent severing device for severing portions of the string 105 from the source of supply, and an intermittent string pulling device whereby string is taken from a source of supply and positively pulled to points beyond the riveting device after each riveting operation, said severing 110 device being arranged to operate at a point between the intermittent string pulling device and the riveting device, and said intermittent string pulling device including string pulling means located beyond the 115 riveting device so as to act directly upon the free portion of the string supply after each severing operation.

5. In a machine for attaching string to envelops, the combination of means for attaching an eyelet and a washer to an envelop, said means comprising a riveting device whereby the string is secured with the eyelet and washer, a severing device for severing portions of the string from the 125 source of supply, said severing device being arranged to operate between the riveting device and said source of supply, and an intermittent string pulling device whereby string is positively pulled from the source 130

of supply after each riveting operation, said intermittent string pulling device including a movable gripper provided with gripping elements whereby the string is gripped, and 5 means for moving said gripper away from the secured end of the severed portion of the string to pull another portion of the string from the source of supply.

6. In a machine for attaching string to 10 envelops, the combination of washer applying means whereby the string is secured to the envelops, a severing device for severing portions of the string from the source of supply, said severing device being arranged 15 to operate in the path of the string at a point between said source of supply and the washer applying means, and an intermittent string pulling device whereby a portion of the string is pulled through the washer 20 before the latter is secured to an envelop, said intermittent string pulling device including a movable gripper carrier provided with gripping elements whereby the string is gripped and secured to said gripper carrier, and means for moving said gripper carrier away from the secured end of the 25 severed portion of the string so as to pull another portion of the string from the source of supply.

7. In a machine for attaching string to 30 envelops, the combination of washer applying means whereby portions of the string are secured to the envelops, a severing device for severing said portions of the string 35 from a source of supply, and an intermittent string pulling device whereby string is pulled from the source of supply after each washer applying operation, said intermittent string pulling device including 40 a movable gripper provided with gripping elements, the path of said movable gripper being intersected by the path of the string at a point between said source of supply and the washer applying means, means for closing 45 said gripping elements at a predetermined point to grip the string, and means for opening said gripping elements at another predetermined point to release the string, thus predetermining the length of 50 the string to be severed.

8. In a machine for attaching string to 55 envelops, the combination of washer applying means whereby portions of the string are secured to the envelops, a severing device for severing said portions of the string from a source of supply, and an intermittent string pulling device whereby string is pulled from the source of supply after each washer applying operation, said intermittent 60 string pulling device including an oscillatory arm, gripping elements carried by said oscillatory arm, means for moving said oscillatory arm to locate the gripping elements at opposite sides of the string, means 65 for closing said gripping elements to grip

the string, means for moving said arm and the closed gripping elements away from the secured end of the severed portion of the string so as to pull another portion of the string from the source of supply, and 70 means for opening the gripping elements at a predetermined point to release the string, thus predetermining the length of string to be severed.

9. In a machine for attaching string to 75 envelops, the combination of washer applying means whereby portions of the string are secured to the envelops, a severing device for severing said portions of the string from a source of supply, and an intermittent string pulling device whereby string is pulled from the source of supply after each washer applying operation, said intermittent string pulling device including 80 a movable gripper provided with a gripping device, a spring tending to close said gripping device, a latch for retaining the gripping device in an open position, a tripping device for unlocking the latch to permit the spring to close the gripping device, 85 and a cam for opening the gripping device to release the string therefrom.

10. In a machine for attaching string to 90 envelops, the combination of washer applying means whereby portions of a continuous string are secured to the envelops, a severing device for severing said portions of the string from a source of supply, an intermittent string pulling device whereby a portion of the string is pulled from the 95 source of supply after each washer applying operation, said severing device being located between said intermittent string pulling device and the washer applying means, and means for adjusting said intermittent 100 string pulling device to predetermine the length of said portions of the string.

11. In a machine for attaching string to 110 envelops, the combination of washer applying means whereby portions of a continuous string are secured to the envelops, a severing device for severing said portions of the string from a source of supply, an intermittent string pulling device whereby a portion of the string is pulled from the 115 source of supply after each washer applying operation, said intermittent string pulling device comprising a movable gripper, a spring for closing said gripper to grip the string, means for moving said gripper 120 to pull the string, an opening device for opening the gripper to release the string from the moving gripper, said spring and a portion of the opening device being carried with the moving gripper, and means 125 for adjusting said opening device to predetermine the length of said portions of the string.

12. In a machine for attaching string to 130 envelops, the combination of washer apply-

- ing means whereby portions of a continuous string are secured to the envelopes, a severing device for severing said portions of the string from a source of supply, an 5 intermittent string pulling device whereby a portion of the string is pulled from the source of supply after each washer applying operation, said intermittent string pulling device comprising a movable gripper, 10 means for closing said gripper to grip the string, means for oscillating said gripper to pull the string, an opening device for opening the gripper to release the string from the moving gripper, said opening device 15 vice including a cam actuated operating member moving in a circular path with the gripper, a stationary cam in said circular path, and a support to which said stationary cam is adjustably secured.
- 20 13. In a machine for attaching string to envelopes, the combination of washer applying means whereby portions of the string are secured to the envelopes, and a combined severing and pulling device comprising a movable carrier, a gripping device secured to said carrier, a string-cutting blade secured to said carrier, means for actuating said gripping device to grip the 25
- string, means for moving said carrier to pull the string, at the same time moving 30 said blade with the carrier to sever the string, and means for opening said gripping device to release the string therefrom.
14. In a machine for attaching string to envelopes, the combination of means for securing an eyelet and a washer to an envelop, 35 said means comprising a riveting device whereby the string is secured with the eyelet and washer, a washer holding device adapted to hold a row of perforated washers, means for feeding the washers, one at a time, from the delivery end of said row to said riveting device, an intermittent string-pulling device for pulling the string through said row of perforated washers, a 40 string-cutting device associated with said pulling device to sever the string at a point near the washer while the latter is secured to the riveting device, and means for actuating said string-pulling device to pull 45 the string from the source of supply, through the row of washers and away from the secured washer.

In testimony that I claim the foregoing
I hereunto affix my signature.

CHARLES F. PFLANZE.
